UNITED STATES PATENT OFFICE.

NICOLAI GRIBOJEDOFF, OF RASTATT, GERMANY.

AIR COMPRESSOR.

Application filed October 20, 1925. Serial No. 63,689.

To all whom it may concern:

Be it known that I, NICOLAI GRIBOJEDOFF, formerly a citizen of Russia, residing at Rastatt, Baden, Germany, have invented certain new and useful Improvements in Air Compressors (for which I have filed an application for patent in Germany March 30th, 1925), of which the following is a specification.

10 My invention relates to a piston compressor having its cylinder rotating about its own axis, and a stationary annular valve enclosing the cylinder head, the ports in the annular valve operating with corresponding 15 ports in the cylinder head to control the admission and the exhaust.

According to my invention the admission is effected through the space between the cylinder head and a cover plate mounted upon 20 the annular valve, and the exhaust through hollow spaces in the annular valve. By these means not only is the construction considerably simplified but the cylinder head is effectively cooled without the use of special 25 means for the purpose. The cylinder head may be formed as a blower, whereby a small super-pressure is produced in the admission chamber and thus admission to the cylinder is facilitated. The cylinder may be pro- 30

vided in known manner with a jacket extending from the crank casing to a position above the cylinder head. In these circumstances the space between the cylinder and the jacket is according to my invention di- 35 vided by the annular valve into the admission chamber and a cooling chamber, and air may be drawn in by suction through the cooling chamber, which is in communication with the admission chamber, thereby ren- 40 dering a separate cooling apparatus unnecessary. The cylinder may, furthermore, be provided in the cooling chamber with screw-like vanes which act as a ventilator upon the air drawn in.

45 The accompanying drawings illustrate an air compressor according to my invention, Figures 1 and 2 being longitudinal sections of the whole engine on the lines 1-1 or 2-2 of Figure 3 respectively, and Figure 3 being a cross-section of the cylinder head, the annular valve and the jacket on the line 3-3 of Figures 1 and 2.

The crank shaft *a* causes by means of the connecting rod *b* the piston *c* to reciprocate vertically in the compressor cylinder *d* which is mounted at the top and at the bot-

tom upon ball bearings, and at the same time causes the cylinder *d* to rotate about its axis by means of the bevel gear *e-f*, the cylinder making one-quarter of a revolution at 60 each single stroke of the piston. The cylinder is surrounded by a stationary jacket *i*, which extends from the crank casing *g* to a position above the cylinder head *h*. The jacket *i* carries a hollow annular valve *k* 65 which is also stationary and surrounds the cylinder head *h*, and which has mounted upon it a two-part cover-plate *l-m*.

The space between the cylinder *d* and its head *h*, on the one hand, and the jacket *i* 70 and the cover-plate *l-m*, on the other hand, is divided by the annular valve *k* into an upper admission chamber *n* and a lower cooling chamber *o*. These two chambers are in communication with each other by a tube 75 *p*, which at one end is connected by a flange to an opening *q* (Fig. 1) of the jacket *i*, and at the other end has its nozzle *r* passing through an opening in the part *m* of the cov- 80 er-plate into the admission chamber *n*.

The hollow space in the annular valve *k* is divided by transverse walls into two op- 85 positely disposed admission chambers *s* (Figs. 1 and 3) and two opposite exhaust chambers *t* (Figs. 2 and 3). The chambers *s* are open at the top, and thus communi- 90 cate with the admission chamber *n*, while the chambers *t* are in communication by ports *u* in the outer wall of the annular valve *k*, and by an annular groove *v* in the jacket *i* extending around the valve with the exhaust pipe *w* mounted upon the jacket.

The peripheral wall of the cylinder head *h* is provided with two pairs of super-posed 95 ports *x* which are diametrically opposite with respect to each other, (Figs. 2 and 3). The inner wall of the annular valve *k* is provided with four ports *y* spaced apart at distances of 90° (Figs. 1-3), of which two 100 adjacent ports are provided at the level of the upper ports *x* and the two others at the level of the lower ports *x*.

The space above the piston *c* in the cylinder *d*, during the greater second part of each downward movement of the piston com- 105 municates alternately through one or the other of the upper ports *x* and the opposite lower port *x*, and also through one of the upper ports *y*, and the opposite lower port 110 *y*, with both the admission chambers *s*, and during the same part of each upward move-

ment of the piston through the same ports x , and through both the other ports y with the exhaust chambers t . Thus the piston c in its downward movement draws air into 5 the cylinder d through the nozzle r , the chamber n and the chambers s . This air is compressed during the first part of the upward movement, during which the cylinder is closed against all the chambers s and t , 10 and is forced out during the second part of the upward movement through the chambers t , the ports u , the annular groove v and the pipe w .

Suction is not only effected directly 15 through ports p' of the tube p provided above the nozzle r , but also through the crank casing g , through the chamber o which is in communication with the crank casing g by way of the spaces between the 20 cylinder d and the jacket i , through the opening q in the jacket and through the tube p . The air drawn-in is forced outward in the chamber n by means of blades z cast on the cylinder head h , and the air 25 is slightly pre-compressed in the chambers s . The cylinder d is provided in the chamber o with screw like blades z' , which feed the air drawn in through the chamber in the 30 manner of a ventilator.

30 What I claim as my invention and desire to secure by Letters Patent is:

1. In an air compressor in combination, 35 a cylinder rotating about its own axis, a piston reciprocating in said cylinder, a cylinder head provided on said cylinder, a stationary annular valve enclosing said cylinder head, ports in said valve and ports in said cylinder head cooperating with each other to control the admission and the exhaust to and from said cylinder, a cover 40 plate mounted upon said valve, an admission chamber enclosed by said cylinder head, said valve and said cover plate, further admission chambers provided in said valve and 45 communicating with the first said admission chamber, exhaust chambers also provided in said valve, and means for feeding air into the first said admission chamber.

2. In an air compressor in combination, 50 a cylinder rotating about its own axis, a piston reciprocating in said cylinder, a cylinder head provided on said cylinder, a stationary annular valve enclosing said cylinder head, ports in said valve and ports in 55 said cylinder head cooperating with each other to control the admission and the exhaust to and from said cylinder, a cover plate mounted upon said valve, an admission chamber enclosed by said cylinder head, said 60 valve and said cover plate, further admission chambers provided in said valve and communicating with the first said admission chamber, exhaust chambers also provided in said valve, means for feeding air into the 65 first said admission chamber, and blades

provided on said cylinder head for forcing the air in this chamber outward and pre-compressing the same in said further admission chambers.

3. In an air compressor in combination, 70 a cylinder rotating about its own axis, a piston reciprocating in said cylinder, a cylinder head provided on said cylinder, a stationary annular valve enclosing said cylinder head, ports in said valve and ports in 75 said cylinder head cooperating with each other to control the admission and the exhaust to and from said cylinder, a cover plate mounted upon said valve, and admission chamber enclosed by said cylinder head, 80 said valve and said cover plate, further admission chambers provided in said valve and communicating with the first said admission chamber, exhaust chambers also provided in said valve, a stationary jacket surrounding 85 said cylinder, a cooling chamber provided between said jacket and said cylinder and separated by said valve from the first said admission chamber, means communicating said cooling chamber with said admission 90 chamber, and means for feeding air into 95 said admission chamber.

4. In an air compressor in combination, 100 a cylinder rotating about its own axis, a piston reciprocating in said cylinder, a cylinder head provided on said cylinder, a stationary annular valve enclosing said cylinder head, ports in said valve and ports in 105 said cylinder head cooperating with each other to control the admission and the exhaust to and from said cylinder, a cover plate mounted upon said valve, an admission chamber enclosed by said cylinder head, said valve and said cover plate, further admission chambers provided in said valve 110 and communicating with the first said admission chamber, exhaust chambers also provided in said valve, a stationary jacket surrounding said cylinder, a cooling chamber provided between said jacket and said cylinder and communicating with the first said admission chamber, screw like blades provided on said cylinder and in said cooling 115 chamber, and means for feeding air into the first said admission chamber.

5. In an air compressor in combination, 120 a cylinder rotating about its own axis, a piston reciprocating in said cylinder, a cylinder head provided on said cylinder, a stationary annular valve enclosing said cylinder head, ports in said valve and ports in 125 said cylinder head cooperating with each other to control the admission and the exhaust to and from said cylinder, a cover plate mounted upon said valve, an admission chamber enclosed by said cylinder head, said valve and said cover plate, further admission chambers provided in said valve and communicating with the first said admission chamber, exhaust chambers also provided 130 in said valve, and means for feeding air into the first said admission chamber.

vided in said valve, a stationary jacket surrounding said cylinder, a cooling chamber provided between said jacket and said cylinder and communicating with the first said admission chamber, screw like blades provided on said cylinder and in said cooling chamber, means for feeding air into the first said admission chamber, and blades provided on said cylinder head for forcing the air in this chamber outward and pre-compressing the same in said further admission chambers.

6. In an air compressor in combination, a cylinder rotating about its own axis, a piston reciprocating in said cylinder, a crank casing, a crank shaft journaled in said crank casing, a rod connecting said piston to said crank shaft, a stationary jacket integral with said crank casing and surrounding said cylinder, a cylinder head provided on said cylinder, a stationary annular valve carried by said jacket and enclosing said cylinder head, ports in said valve and ports in said cylinder head cooperating with each other to control the admission and the exhaust to and from said cylinder, a cover plate mounted upon said valve, an admission chamber enclosed by said cylinder head, said valve and said cover plate, further admission chambers provided in said valve and communicating with the first said admission chamber, exhaust chambers also provided in said valve, a cooling chamber provided between said jacket and said cylinder and separated by said valve from the first said admission chamber, a tube connecting said cooling chamber to the first said admission chamber, screw like blades provided on said cylinder and in said cooling chamber, ports provided in said tube for admitting air into the first said admission chamber, and blades provided on said cylinder head for forcing the air in this chamber outward and pre-compressing the same in said further admission chambers.

said tube for admitting air into the first said admission chamber.

7. In an air compressor in combination, a cylinder rotating about its own axis, a piston reciprocating in said cylinder, a crank casing, a crank shaft journaled in said crank casing, a rod connecting said piston to said crank shaft, a stationary jacket integral with said crank casing and surrounding said cylinder, a cylinder head provided on said cylinder, a stationary annular valve carried by said jacket and enclosing said cylinder head, ports in said valve and ports in said cylinder head cooperating with each other to control the admission and the exhaust to and from said cylinder, a cover plate mounted upon said valve, an admission chamber enclosed by said cylinder head, said valve and said cover plate, further admission chambers provided in said valve and communicating with the first said admission chamber, exhaust chambers also provided in said valve, a cooling chamber provided between said jacket and said cylinder and separated by said valve from the first said admission chamber, a tube connecting said cooling chamber to the first said admission chamber, screw like blades provided on said cylinder and in said cooling chamber, ports provided in said tube for admitting air into the first said admission chamber, and blades provided on said cylinder head for forcing the air in this chamber outward and pre-compressing the same in said further admission chambers.

In testimony whereof I affix my signature.

NICOLAI GRIBOJEDOFF.
